UNITED STATES PATENT OFFICE.

CHARLES H. PASCHALL, OF CHICAGO, ILLINOIS.

SCREEN-OPENING.

1,094,927.

Specification of Letters Patent. Patented Apr. 28, 1914.

Application filed October 12, 1911. Serial No. 654,348.

To all whom it may concern:

Be it known that I, CHARLES H. PASCHALL, a citizen of the United States, residing at Chicago, in the county of Cook and State of Illinois, have invented certain new and useful Improvements in Screen-Openings, of which the following is a specification.

My invention relates to improvements in screened openings, and has for its salient object to provide in association with a pivoted window sash, or the like, a screen structure arranged to permit the opening or closing of the sash without interference with or movement of the screen structure, and arranged adequately to screen the opening regardless of the extent to which the pivoted sash is opened.

In the drawing, wherein I have illustrated an embodiment of my invention particularly adapted for factory window or sky-light purposes, by way of disclosure of one form of the invention: Figure 1 is a perspective view of a section of the structure; and Fig. 2 is an enlarged detail of a fragment of the frame and screen.

In such drawing 5 indicates the frame, preferably of angle iron, providing a band 6, 6', to bound the four sides of the opening. Connected with said band, preferably integrally, are flanges 7 and 7', lying respectively in the planes of opposite edges of the band 6, 6', or, as I may term it, along the interior and exterior planes, respectively, of the opening. For convenience the frame structure may be made of two pieces of angle iron with their body portions 6 and 6' meeting near the middle of the vertical sides of the frame, the adjacent ends of the flanges 7, 7' being vertically separated a short distance to afford an opening 8 between them as shown in Fig. 2. The two sections of the frame may, of course, be duplicates in construction, reversely faced, and the two sections may be secured together in any suitable fashion. Specifically I prefer that all four sides of the body 6 have secured thereto channel bars 9 to receive sky-light glass, or that other provision be made for the appropriate setting of the frame in its intended position. With the specific construction shown, however, the two sections of the frame may adequately be secured together by riveting them, as at 10, to the vertical chamber bar 9. To the flanges 7 at the edge of the opening 8 I provide hinge members

11, of suitable construction, coöoperating with complementary hinge members 11', secured to the side frame members of a swinging sash 12, suitably constructed neatly to close the apertures when swung to vertical or closed position, and provided with any suitable latch 13 for holding it closed. Manifestly, the arrangement of the flanges 7—7' leaves the sash 12 free to swing, as shown in Fig. 1, from vertical closed position to horizontal fully open position, the sash 12 when fully opened lying horizontally in the opening 8 between the flanges 7—7', as indicated in Fig. 2.

The screen is made of two sections, 14—14', each preferably substantially coextensive with, and secured to, the corresponding flanges 7—7', so that the screen sections lie on opposite sides of the pivotal axis of the sash and confront opposite faces of the sash. Each screen may have a border frame 15, appropriate portions of which may be riveted, as at 16, or otherwise secured to the confronting, or inner, faces of the respective flanges 7—7'. The contiguous frame members 15 of two screen sections may, if desired, be equipped with yielding filler strips 17 in the form of felt tubes, or the like, for exact contact with the window glass at all times, but in commercial practice I find that the approximation to a fit afforded by a straight-edge screen frame is usually sufficiently close for practical purposes.

It will be noted that, with an open hinge structure, as at 11, 11', the sash may readily be lifted out of the frame, passing easily through the gap between the screens and the opening 8 between flanges 7, 7'.

While I have herein described in some detail a specific embodiment of my invention, some details of which I may claim for their intrinsic novelty and value, it will be understood by those skilled in the art that changes in the construction may be made without departure from the spirit of my invention and within the scope of the appended claim.

What I claim is:

The combination of a frame bounded by angle irons, each angle iron having one of its flanges lying respectively in the plane of the rear or front face of the frame accordingly as it is above or below the center of the frame, and its other flange lying within the frame for attachment thereto to support the angle irons, upper and lower screen

members respectively secured to the inner faces of the rear and front flanges, whereby the flanges form protective borders for the corresponding edges of the screen members, 5 the secured edges of the screen members lying in the corner between the flanges of the angle irons and the free edges of said screen members being spaced apart horizontally a distance determined by the distance between the planes of the upper and lower 10 flanges and vertically a distance to accommodate a sash, and a sash pivoted in the frame for swinging movement between the free edges of said screen members.

In testimony whereof I hereunto set my hand in the presence of two witnesses.

CHARLES H. PASCHALL.

In the presence of—

W. LINN ALLEN,
MARY F. ALLEN.
